US00D843839S

(12) **United States Design Patent** (10) Patent No.: **US D843,839 S**
(45) Date of Patent: **** Mar. 26, 2019**

(54) **BOTTLE**

(71) Applicants: **Jillian Walbroel**, Woodland Park, NJ (US); **Christon G. Suess**, Paramus, NJ (US); **Jeffrey Steel**, Hoboken, NJ (US); **Carl Cetera**, Westfield, NJ (US)

(72) Inventors: **Jillian Walbroel**, Woodland Park, NJ (US); **Christon G. Suess**, Paramus, NJ (US); **Jeffrey Steel**, Hoboken, NJ (US); **Carl Cetera**, Westfield, NJ (US)

(73) Assignee: **Cotapaxi Custom Design and Manufacturing LLC**, Carlstadt, NJ (US)

(**) Term: **15 Years**

(21) Appl. No.: **29/616,068**

(22) Filed: **Sep. 1, 2017**

Related U.S. Application Data

(63) Continuation of application No. 29/561,021, filed on Apr. 12, 2016, now Pat. No. Des. 796,328, which is a continuation of application No. 29/551,506, filed on Jan. 14, 2016, now abandoned.
